UNITED STATES PATENT OFFICE

153,398

DESIGN FOR A POWER-OPERATED HAND TOOL

Arthur W. Smith, Los Angeles, Calif.

Application May 27, 1946, Serial No. 130,131

Term of patent 14 years

(Cl. D54—14)

To all whom it may concern:

Be it known that I, Arthur W. Smith, a citizen of the United States of America, residing in the city of Los Angeles, in the county of Los Angeles, State of California, have invented a new, original, and ornamental Design for a Power Operated Hand Tool of which the following is a specification, reference being had to the accompanying drawing, forming a part thereof.

Fig. 1 is a perspective view of a power operated hand tool, showing my new design; and

Fig. 2 is a rear end elevational view thereof.

The other side of the device is the same as the side shown in Fig. 1.

The dominant features of the design reside in the portions shown in full lines.

I claim:

The ornamental design for a power operated hand tool, substantially as shown and described.

ARTHUR W. SMITH.
